OXY-FUEL GAS POWDER-LADEN CUTTING
OXYGEN NOZZLE

Edward M. Holub, Elizabeth, N. J., assignor to
The Linde Air Products Company, a corpora-
tion of Ohio

Application September 3, 1947, Serial No. 771,907

4 Claims. (Cl. 110—22)

1

This invention relates to blowpipe nozzles for thermo-chemically cutting, deseaming, or scarfing steel with a stream of oxygen and oxy-fuel gas preheat flames, and more particularly to such nozzles which discharge adjuvant powder containing iron, for example, in the cutting oxygen stream to assist the reaction in deseaming or scarfing difficult-to-cut metals such as stainless steel, cast iron and the like.

The conventional oxy-fuel gas nozzle which is adapted to be used without powder in the cutting oxygen stream, is provided with a cylindrical skirt surrounding the preheat oxy-fuel gas jets to prevent the flames from blowing off the nozzle tip. In the past, operation of such conventional cylindrically-skirted type of oxy-fuel gas nozzle proved to be quite impractical in powder cutting, scarfing and deseaming due to objectional fusing and sintering of powder which collected in the skirt between the preheat flames.

Such accumulation of powder in the form of globules inside the skirt not only interfered with the preheat gas flow, causing the flames to be unstable and of insufficient temperature to burn the powder, but also actually distorted the cutting oxygen stream so that the operation had to be discontinued while the built-up powder accumulation was removed from the skirt. Thus, much time was lost due to the necessity for stopping the deseaming or scarfing operation to clean out the burned or sintered powder in the skirt to restore the scarfing efficiency of the nozzle. Previous attempts to solve the problem were entirely unsuccessful prior to the present invention.

The main object of this invention is to eliminate such serious objection of the use of adjuvant powder in the cutting oxygen stream of oxy-fuel blowpipe nozzles for cutting, scarfing and deseaming operations.

According to the invention, a novel oxy-fuel gas powder-laden cutting oxygen nozzle is provided in which an oxy-fuel gas jet expanding space is located between an inner tip surrounding the powder-laden cutting oxygen passageway and an outer skirt, in lateral communication with each of the oxy-fuel gas outlets, so that, in effect, the preheat jets pass between the internal tip and the external skirt, the internal tip protruding an appreciable distance or substantial amount beyond the external skirt to cause the powder in the cutting oxygen stream to burn completely outside of the nozzle. The result is that no portion of the powder builds up in a fused mass to obstruct the flow of the preheat flame and cut-

2

ting gases, as in the case of conventional oxy-fuel gas nozzles.

Results with the nozzle of the present invention are excellent, not only with acetylene fuel but also with other fuel gases, since the difficulties previously encountered with the conventional oxy-fuel gas nozzle are eliminated. Heretofore, no practical powder scarfing nozzle was available which could use fuel gas other than acetylene.

10 In the drawing:

Fig. 1 is a fragmentary view, mainly in longitudinal cross-section, of an oxy-fuel gas powder scarfing nozzle illustrating the invention;

15 Fig. 2 is an enlarged view in front end elevation;

Fig. 3 is a similar view of the nozzle in rear end elevation; and

20 Fig. 4 is a fragmentary perspective view of the front end portion of the nozzle, part of the outer skirt being broken away to show the internal construction.

25 As shown in the drawing a nozzle N is provided which includes an elongated body 10, composed of copper, having a central longitudinally extending powder-laden cutting-oxygen passage 12 and an annular series of longitudinally extending oxy-fuel gas passages 14 surrounding such central passage 12. The rear end portion of the cutting oxygen passage 12 contains a spud 16 composed of brass, having a central cutting oxygen passage 18 and an annular flange 20 provided with an annular series of adjuvant powder discharge grooves 22.

30 An annular recess in the spud 16 cooperates with the internal wall of the passage 12 in the body 10 to provide an annular powder distributing space 24 communicating with the grooves 22, the nozzle body 10 having an annular series of forwardly and inwardly inclined powder inlet 35 passages 26 leading to the space 24.

35 The nozzle N is adapted to be connected to a powder deseaming blowpipe or desurfacing head (not shown) in a conventional manner, and is provided with a captive nut 28 for securing the nozzle to the blowpipe head. Commercially pure oxygen is delivered to the passage 18, a combustible mixture of oxygen and fuel gas, such as acetylene, butane, propane, city gas, etc., is delivered to the inlet ends of the passages 14, and adjuvant powder composed mainly of iron, for example, is delivered to the powder inlets 26 with any suitable gas under pressure by the blowpipe or scarfing head, not shown, to which the nozzle is attached, all in a manner well known to those 50 skilled in the art.

The nozzle body 10 is also provided with an internal tip 30 as shown in the drawing, which surrounds the powder laden cutting oxygen orifice 32 of the passage 12 and extends for a distance of the order of 0.030 inch beyond the front end surface 34 of an annular outer sleeve or skirt 35, composed of copper. The passage 12 as well as the oxy-fuel gas preheat holes or passages 14 of the nozzle continue straight through the tip 30.

The front end portion of the body 10 is provided with an annular recess 36 which intersects the lateral walls of the outer end portions 37 of the passages 14, so that the front view of the body 10 presents a scalloped effect as illustrated in Figs. 2 and 4.

The outer skirt 35 which is relatively thick bears at its inner end against an annular shoulder and is silver soldered or bronze welded to the nozzle body 10 at 38. The inner wall of the skirt 35 cooperates with the recess 36 to form an annular space 39 which communicates with each of the end portions 37 of the oxy-fuel gas passages 14, permitting expansion of the oxy-fuel gas jets to insure the production of preheat flames which are stable and to prevent such flames from blowing off.

In operation, powder enters the nozzle N through the inlets 26 at the rear of the nozzle and is discharged through the passages 22 into the cutting oxygen passage 12 where it mingles with the cutting oxygen stream, the powder-laden oxygen stream being discharged through the orifice 32 in downstream relation with respect to the oxy-fuel gas discharge ports 40. As a result, powder sintering on the inside of the skirt 35 is entirely eliminated, yet hot stable preheat flames are produced and, because of this, entirely satisfactory scarfing speeds are obtained with the nozzle of the present invention.

I claim:

1. An oxy-fuel gas powder-laden cutting-oxygen nozzle comprising a body having a powder-laden cutting-oxygen passage, said body also having a series of oxy-fuel gas passages arranged about said powder-laden cutting-oxygen passage and an outer peripheral recess laterally intersecting the discharge end portions of said oxy-fuel gas passages, an outer skirt mounted on the end portion of said body in spaced relation to the lateral wall of said recess to provide a space in communication with the discharge end portions of such oxy-fuel gas passages for expansion of the oxy-fuel gas jets to insure the production of stable preheat flames and to prevent the preheat flames from blowing off, the end surface of said outer skirt terminating a substantial amount upstream with respect to the front end surface of the body adjacent the discharge end of said powder-laden cutting-oxygen passage, so that, in effect an inner tip is provided about the discharge end of such passage which protects the oxy-fuel gas jet expansion space from objectionable powder accumulation.

2. An oxy-fuel gas powder-laden oxygen-

scarfing nozzle comprising a body having a central longitudinally extending cutting oxygen passage and an annular series of longitudinally extending oxy-fuel gas passages disposed around said central passage, passage means for feeding adjuvant powder composed mainly of iron into said cutting oxygen passage, an outer skirt mounted on said nozzle body, to provide an oxy-fuel gas jet expansion space, the front end surface of said skirt being disposed an appreciable amount back of the front end portion of the nozzle body, so that the cutting oxygen laden with adjuvant powder is discharged downstream with respect to the oxy-fuel gas discharged from said oxy-fuel gas jet expansion space, and hot stable oxy-fuel gas preheating flames are produced with the elimination of sintered powder accumulations on the inside of said skirt.

3. A blowpipe nozzle comprising an elongated body having a central cutting oxygen passage and an annularly arranged series of oxy-fuel gas passages disposed around such central passage, said nozzle being provided with an inner tip at the outlet orifice of such central passage, which extends downstream with respect to the outlet orifices of such oxy-fuel gas passages, so that adjuvant powder discharged with the cutting oxygen stream is prevented from accumulating in the oxy-fuel gas outlet orifices, and means providing an outer skirt surrounding and communicating laterally with such oxy-fuel gas outlet orifices to prevent the preheating flames produced by the oxy-fuel gas jets from blowing off, the front end surface of said outer skirt being located a substantial distance upstream with respect to the front end surface of said inner tip.

4. A blowpipe nozzle comprising the combination of an elongated body composed of copper having a longitudinally extending passage for discharging a powder laden stream of cutting oxygen, said body also having at least one oxy-fuel gas passage for discharging a preheating flame jet composed of a combustible mixture of oxygen and fuel gas, an outer skirt composed of copper mounted on the discharge end portion of said body to provide an expansion space for the oxy-fuel gas jet to prevent the preheating flame from blowing off, and means providing an inner tip at the discharge mouth of said powder laden cutting oxygen stream passage which terminates an appreciable distance downstream with respect to said outer skirt and thereby entirely eliminates any undesirable accumulation of sintered powder in such jet expansion space adjacent the outlet of the oxy-fuel gas passage.
